United States Patent

Des. 236,231
Patented Aug. 5, 1975

236,231

MOTION PICTURE PROJECTOR

Robert E. Bourke, Weston, Conn., assignor to
GAF Corporation, New York, N.Y.

Filed July 27, 1973, Ser. No. 383,396

Term of patent 14 years

Int. Cl. D16—02

U.S. Cl. D61—1 K

FIG. 2

FIG. 1

FIG.3

FIG.4

FIG. 1 is a right side elevational view of a motion picture projector showing my new design, the left side being flat, plain and unornamented.

FIG. 2 is a top plan view thereof;

FIG. 3 is a front elevational view thereof;

FIG. 4 is a rear elevational view thereof.

I claim:

The ornamental design for a motion picture projector, substantially as shown.
